UNITED STATES PATENT OFFICE

120,379

DESIGN FOR A TEXTILE FABRIC

Curt E. Forstmann, Montclair, N. J.

Application November 2, 1939, Serial No. 88,015

Term of patent 14 years

To all whom it may concern:

Be it known that I, Curt E. Forstmann, a citizen of the United States, residing at Montclair, in the county of Essex and State of New Jersey, have invented a new, original, and ornamental Design for a Textile Fabric, of which the following is a specification, reference being had to the accompanying drawing, forming part thereof.

In the drawing, the sole figure is a plan view of a piece of fabric showing the design.

The design of this fabric is an all-over stipple effect background resulting from small stitches lying in various directions, the background being overlain by diagonal line stripes resulting from relatively long rectilinear spaced stitch formations, each composed of several contiguous stitches as shown.

I claim:

The ornamental design for a textile fabric, as shown and described.

CURT E. FORSTMANN,
